FABRIC COATING MACHINE

Francis B. Quinn, Thompsonville, and Robert G. Levitch, Enfield, Conn., assignors to Bigelow-Sanford Carpet Co., Inc., Thompsonville, Conn., a corporation of Massachusetts

Application November 17, 1944, Serial No. 563,858

3 Claims. (Cl. 91—31)

Our invention relates to fabric coating machines and particularly to machines for coating cord fabrics with a rubber solution, such fabrics being used in vehicle tires.

The object of the invention is to improve the efficiency of such machines and to remedy the defects experienced in previous machines of this sort.

Fig. 1 shows a cross-section of our machine, and

Fig. 2 shows a modification.

Referring to Fig. 1, the chamber A is open at the top and bottom and has sides A₁ and A₂. It is supported on a frame above a trough A₄ containing the rubber solution. A roll 6 dips into the rubber solution in the tank and carries the fabric into and out of the tank. Located above the roll 6 is a guide roll 5 which guides the fabric from the chamber to the roll 6.

Above the chamber is a guide roll 1, which is so positioned with relation to the guide roll 5, that the entering dry cloth, which passes over guide roll 1 from a source of supply, is held in contact with the outside surfaces of the rolls 2, 3 and 4 which are arranged vertically above one another in the chamber. Located in the chamber opposite the spaces between rolls 2 and 3 and between 3 and 4 are rolls 7 and 8. The rolls are so related to one another that the dry cloth passes down in contact with the outside surfaces of rolls 2, 3 and 4, and, after passing through the solution and around dip roll 6, the wet cloth passes upwards in contact with the inside surfaces of the rolls 4, 1, 3, 8 and 2 to the guide roll 9 and thence to the usual drying chamber, not shown.

The rolls 2, 3, 4, 7 and 8 are adjustable sidewise and preferably are about 4 to 6 in. in diameter, are of polished steel and are rotated at high speed, by any suitable means, not shown, so that they thus have a surface speed of about 15 to 30 ft. per second, preferably in the direction of the feed of the cloth. The rolls, due to their high surface speed burnish the cloth and effectively remove excess solution from the surfaces of the cloth and throw some of it by centrifugal force against the sides A₁, A₂ of the chamber on which it drips down into the tank below. The rolls 4, 3 and 2 apply some of the excess solution, removed by them from the fabric, to the incoming cloth which wipes these rolls and keeps them in a clean condition whereby their efficiency in removing excess solution from the fabric is greatly enhanced.

In the apparatus of Fig. 2, the incoming cloth wipes not only the rolls 2, 3 and 4, but also the

rolls 8 and 1, the cloth being carried, as shown, about the rolls 5, a, b, c and d.

The cloth is pulled through the apparatus by any suitable means, not shown.

By means of this arrangement, one or both sets of burnishing rolls are cleaned by the ingoing fabric and the efficient removal of excess solution from the fabric is achieved and consequently a solution of higher solids content may be employed than has been the previous practice and because of the low moisture content in the fabric a higher drying speed may be used than has been customary. Thus the machine enables high production efficiency and low production cost to be attained.

We claim:

15. 1. A fabric coating machine having in combination a chamber open at top and bottom and having vertical sides, two sets of burnishing rolls therein, said rolls being rotated with a surface speed of from 15 to 30 feet per second, the rolls in each set being in alignment with each other, a tank located below said chamber and adapted to contain a rubber solution, a roll dipping into said tank, means to guide the incoming dry fabric against the sides of the rolls of one set with 10 which sides the wet fabric does not contact and means to guide the wet fabric against the opposite sides of said rolls and against the other set of rolls in said chamber.
20. 2. In fabric coating apparatus having a tank for holding a coating solution and opposed sets of burnishing rolls for removing excess solution coated on fabric passed through the tank, in combination, guide rolls for directing a fabric from a source of supply through the tank, and thence 15 between and against opposed faces of the burnishing rolls, including guides directing the fabric, prior to its passage through the tank, against and across the outside faces of the burnishing rolls of at least one set.
25. 3. In fabric coating apparatus having a tank for holding a coating solution and opposed sets of burnishing rolls for removing excess solution coated on fabric passed through the tank, in combination, guide rolls for directing a fabric from a source of supply through the tank, and thence 20 between and against opposed faces of the burnishing rolls, including guide rolls directing the fabric, prior to its passage through the tank, against and across the outside faces of both sets of the burnishing rolls.
